This technical drawing illustrates a window frame assembly. The frame is defined by a main outer border (6) and an inner border (7). The top section (14) features a handle (15) and a lock (16). The bottom section (17) includes a handle (18) and a lock (19). The left and right sides (13) are secured with bolts (9). The central area (3) contains a grid of circular holes. The drawing uses a combination of solid lines for the frame and dashed lines for internal components and assembly lines.

Sellers.

UNITED STATES PATENT OFFICE.

JOHN M. ALDERFER, OF SHARON CENTRE, OHIO.

CRATE.

SPECIFICATION forming part of Letters Patent No. 600,821, dated March 15, 1898.

Application filed April 3, 1897. Serial No. 630,502. (No model.)

To all whom it may concern:

Be it known that I, JOHN M. ALDERFER, a citizen of the United States, residing at Sharon Centre, in the county of Medina and State of Ohio, have invented a certain new and useful Improvement in Crates, of which the following is a specification.

My invention has relation to improvements in crates in which fruits and vegetables are placed for shipment or temporary storage, and it has especial relation to that class of crates that are susceptible of being partially folded or collapsed for economy of space in shipment or storage when empty.

15 The object of my invention is to produce a new and improved crate of the class specified and to secure strength in the ends to prevent the weight of the load tearing apart the pieces of which the crate is constructed when 20 it is lifted and provide an improved method of attaching and locking the bottom and cover in place.

To the aforesaid objects my invention consists in the peculiar and novel construction, 25 arrangement, and combination of parts hereinafter described, and then specifically pointed out in the claims, reference being had to the accompanying drawings, forming a part of this specification.

30 In the accompanying drawings, in which similar reference-numerals indicate like parts in the different views, Figure 1 is a plan of the crate expanded and the cover in place; Fig. 2, an end elevation; Fig. 3, a side elevation; Fig. 4, an inverted plan of the bottom; Fig. 5, a view of the upper portion of one corner; Fig. 6, a plan of the body of the crate partially collapsed; and Fig. 7, a vertical longitudinal section, enlarged, of the complete 40 crate at the line xx of Fig. 1.

Referring to the figures, 11 are the sides, which consist each of two upright slats 22, to which are fastened cross-slats, the upper and lower 33 being thicker than the intermediate ones and extending beyond them at each end.

Each end of the crate consists of two heavy sticks 45, preferably square, united near their ends by vertical slats 66, these latter 50 being united near their upper ends by a cross-slat 7, and shorter intermediate slats 88 unite the slat 7 and stick 5, thus leaving a

hand-space under the stick 4. The ends of the upper and lower slats 3 of the sides rest adjacent to and outside the ends of the sticks 55 45, and all are perforated with holes that register vertically. The sides and ends are united at the corners by metallic rods or wires 9, the central portions of which rest lengthwise under the sticks 5, and are bent and pass 60 upward through the holes in the sticks 5, 3, 3, and 4, and are bent lengthwise along the top of the latter toward the center from each end, and the ends are made fast by being bent down and driven into the stick 4. By 65 this arrangement the sides and ends are practically hinged together at the corners of the crate, so that the body thus formed can be collapsed, the two sides swinging toward each other, as shown in Fig. 6, while the open 70 space under the upper stick of the ends affords space, so that the stick can be grasped by the hand, and the wire serves to take the strain from the wooden parts.

The bottom 10 consists of longitudinal and 75 cross slats, the latter being beneath and arranged to abut the bars 5 of the ends and the longer ones resting on said bars, and on its under face is a slat 11, pivoted to one of the longer slats and adapted to swing across 80 under the lower side bars 3 and lock the bottom in place.

The top 12 consists of cross-slats 13 of such length as to rest at each end on the upper bars 3 of the sides and longitudinal slats 14, 85 attached to the cross-slats, the cross-slats 13 being slightly closer together than the sticks 4, and the slats 14 longer than the space between the sticks 4. In one of the slats 14 is an opening 15, in which fits a wedge-shaped 90 key 16, and in placing the top in position the ends of slats containing the opening 15 are inserted under the adjacent upper bar 4 and the cover dropped down on the crate. It is then pushed until its opposite end passes under the opposite bar 4 and until its further progress is arrested by the adjacent slat 13 meeting the cross-slat 14, when the key 16 is inserted in the opening 15 and the top securely locked in place.

When it is desired to fold the crate, the top and bottom are removed and placed edgewise in the body. The latter is then collapsed, as shown in Fig. 6, and held by hooks 17, pivot-

ally attached to the upper and lower bars of one side, entering corresponding eyes 18 in the opposite side.

I claim as my invention—

- 5 1. In a collapsible crate-body, the combination with sides and ends composed of longitudinal slats fastened to end posts, the upper and lower slats of each extended beyond the intermediate slats and end posts; the extended side slats arranged to rest against and between the extended end slats, and the extended ends vertically perforated in alinement at each corner of the body; of single metallic rods, each having its central portion resting along the bottom of one of the lower end slats, and the ends passed upward through said perforated ends and fastened to the top of the corresponding upper end slat, substantially as shown and described.
- 10 2. In a collapsible crate the combination with sides and ends composed of longitudinal slats fastened to end posts, the upper and lower slats of each extended beyond the intermediate slats and end posts; the extended side slats arranged to rest against and between the extended end slats; the extended ends vertically perforated in alinement at each corner of the body; and single metallic

rods, each having its central portion resting along the bottom of one of the lower end slats, 30 and the ends passed upward through said perforated ends and fastened to the top of the corresponding upper end slat; of a bottom consisting of lengthwise and cross slats the latter being beneath and arranged to abut against the lower slats of the ends, and the former to rest on said slats, and a strip to constitute a bottom, pivoted to the under side of one of the longitudinal slats and adapted to swing and have its ends enter beneath the 35 lower side strips to lock the bottom in place; and a cover adapted to slide under the upper end slats, composed of longitudinal and end slats, the longitudinal slats arranged to slide under the upper end slats, a keyhole in one of said longitudinal slats, and a key adapted to enter said hole all constructed and arranged substantially as shown and for the purpose specified.

In testimony that I claim the above I here- 50 unto set my hand.

JOHN M. ALDERFER.

In presence of—

C. P. HUMPHREY,
C. E. HUMPHREY.
